UNITED STATES PATENT OFFICE.

SIMON WREATON BENSON, OF DENVER, COLORADO.

METAL WINDOW-SCREEN.

SPECIFICATION forming part of Letters Patent No. 782,771, dated February 14, 1905.

Application filed April 12, 1904. Serial No. 202,848.

To all whom it may concern:

Be it known that I, SIMON WREATON BENSON, a citizen of the United States, residing at Denver, in the county of Denver and State of Colorado, have invented a new and useful 5 Metal Window-Screen, of which the following is a specification.

My invention relates to window-screens, and has for its objects to produce a comparatively 10 simple inexpensive device of this character in which the edges of the open-work fabric will be firmly but detachably connected to the screen-frame, thus permitting of the adjustment of the fabric from time to time to 15 maintain the same taut, one in which the hangers may be adjusted as circumstances require and one wherein an adjustable filling plate or member is provided for closing the lateral space between the screen and sash 20 frame.

The invention has for a further object to provide a simple effective lock carried by the screen for maintaining the latter in closed position.

With these and other objects in view the invention comprises the novel features of construction and combination of parts more fully hereinafter described.

In the accompanying drawings, Figure 1 is 30 a rear elevation of a screen embodying my invention. Fig. 2 is a top plan view of the same. Fig. 3 is a detail section on the line 3 3 of Fig. 1. Fig. 4 is a detail perspective view of the lock, showing the parts thereof 35 disconnected. Fig. 5 is a detail section on the line 5 5 of Fig. 1. Fig. 6 is a detail section on the line 6 6 of Fig. 1.

Referring to the drawings, it will be seen 40 that my improved frame comprises a top rail 1, a bottom rail 2, and side stiles 3, which parts when assembled receive and support a sheet of open-work or reticulated material 4, preferably of wire-gauze, as usual. The bars or members of the screen-frame are preferably 45 composed from galvanized sheet metal, and each comprises, as seen more clearly in Fig. 3, a front plate or cap 5 and a rear plate or back 6. The outer plate 5 is provided at its inner edge with an inturned double-folded

flange 7, while the plate 6, which is of substantially U shape in cross-section, has at its inner edge an inturned flange 8, the edge of which bears upon the inner face of the plate 5, and at its outer edge a similar inturned flange 9, the edge of which bears also upon the inner face of plate 5 and terminates in a marginal outturned flange 10, around which the outer portion or edge of the cap-plate 5 is folded, thereby producing upon the rail or bar a stiff outstanding flange, which is united at its ends by rivets or other fastening devices 11, with the ends of the similar flanges upon the adjacent frame bars or members, whereby these united flanges form conjointly around the sides and bottom of the screen-frame a marginal outstanding flange. The stiles and rails are further united by means of end rivets 11', which serve particularly as a means for connecting the top rails to the adjacent ends of the stiles.

As seen in Fig. 5, the formation of the upper rail 5 is identical with that just described except that in this connection the marginal outturned flange 10 is omitted from the in-turned flange 9 of the rear plate 6 and that the outer portion of the plate 5 is folded directly downward upon the flange 9, and thus projects normally horizontally in rear of the screen-frame, to thus constitute the relatively fixed primary portion or section 12 of an adjustable filling plate or member 13, the secondary adjustable portion or section 14 of which is suitably slotted transversely, as at 15, and is attached to the section 12 by suitable fastening devices 16, preferably in the form of bolts or rivets, engaging through said slots, and thereby permitting adjustment of the section 14 for varying the width of the filling member. For further connecting the sections of the filling member I have folded the ends of the primary section 12 backward upon the ends of the section 14, as seen at 17, these folded portions also constituting guides for the section 14 in its movements.

The flanges 7 and 8, carried, respectively, by the front and rear plates of the frame-bar, conjointly form between them and around the inner margin of the screen-frame recesses or

- seats 18, designed to receive the adjacent edges of the fabric 4, which is maintained in place in said seats by means of retaining members or keys 19, preferably in the form of strips 5 of sheet metal inserted edgewise to position and bearing at their inner edges upon the fabric. These keys, which are freely removable to permit releasing of the edges of the fabric for purposes of stretching the latter, 10 are secured in place in the following manner: The keys, which lie along the edges of the stiles and rails, are engaged upon their outer edges by sheet-metal turn-buttons 19', secured in place, as seen in Fig. 6, by the fastening devices 20', which secure together the plates composing the stiles and rails, these buttons being arranged at suitable intervals throughout the length of the latter, while the keys extending along the top and bottom rails may 15 20 have their ends inserted beneath the adjacent edges of the rear plates of the stiles, as illustrated in Fig. 1, to thus obviate the necessity of buttons adjacent to the ends of said keys. Under this arrangement the keys may be readily released and withdrawn for the purpose 25 above mentioned.
- Carried at the upper ends of the marginal outstanding flanges upon the stiles 3 and at the upper ends of the latter are hangers 21, 30 preferably in the form of U-shaped wire members seated between the inwardly-folded portions of the plates 5 and the adjacent flanges 10 on the plates 6, these hangers, the crown portion of which project above the ends of 35 the flanges, being adjustably held in place by means of the fastening devices 11 in the form of screw-bolts having nuts, which in practice may be loosened to permit the longitudinal adjustment of the hangers and again tightened 40 for fixing the latter in their adjusted positions. These hangers are adapted for detachable engagement with engaging members or hooks 22, attached in any appropriate manner to window-sash frame 23.
- 45 Attention is here directed to the fact that in practice when the screen is seated in the sash-frame the outstanding marginal flange will bear upon the adjacent face of the blind-stop, the outer portion or edge of which fits 50 snugly into the angle of the screen-frame, thereby imparting a neat finished appearance and at the same time preventing looseness of the screen within the sash-frame and the passage of insects between the meeting edges of 55 the parts. Furthermore, the filling-plate or member 13 will bear at its inner edge upon the adjacent member of the window-sash to thus prevent the passage of insects and to obviate looseness and rattling of the same, the 60 filling-plate being adjustable for the purposes heretofore mentioned.
- The locking device 20 is removably attached to the bottom rail 2 or other desired part of the screen-frame by means of a through-bolt 24, upon which is seated, at the rear face of 65 the bar, a shouldered bearing member or washer 25, the reduced neck 26 of which constitutes a direct bearing for the pivoted latching member 27, the latter being retained in place by a nut tapped onto the end of the 70 through-bolt. The member 27, which is composed from sheet metal suitably bent to shape, is adapted when in locked position to engage with a member or catch 28, attached to the window-frame, the latch 27 being provided 75 with an inturned flange having an inclined cam-face 29, which acts as the latch moves into engagement with the catch to draw the screen-frame tightly inward upon the sash-frame. 80
- From the foregoing it is apparent that I produce a comparatively simple inexpensive device which is admirably adapted for the attainment of the ends in view, it being understood, however, that minor changes may be 85 resorted to without departing from the spirit of the invention.
- Having thus described the invention, what is claimed is—
1. The combination with a screen-frame including a bar composed of a cap and a back, one of said parts having a flange folded around the marginal face of the other part to form a seat, of a fabric having a portion thereof arranged in said seat, and a retaining member 95 disposed in the seat upon the fabric. 90
  2. The combination with a screen-frame including a bar composed of a cap and a back and provided with a seat of a fabric having a portion thereof arranged in the seat, a removable retaining member disposed in the seat upon the fabric, a turn-button carried by the frame and adapted for engagement with the retaining member to secure the latter in place, and a fastening device connecting the component parts of the bar and securing the turn-button in place. 100 105
  3. The combination with a screen-frame including sheet-metal stiles composed of inner and outer plates, the outer portion of one of said plates being folded around the other, hangers disposed beneath the folded portion of the plates, and fastening devices connecting the plates and securing the hangers in position. 110 115
  4. The combination with a screen-frame including a sheet-metal bar composed of an inner and an outer plate, a portion of one of the plates being folded around the other plate, of a hanger seated beneath the folded portion of the plate, and a fastening device connecting the plates and securing the hanger in position. 120
  5. The combination with a screen-frame including a sheet-metal bar composed of an inner and an outer plate, a portion of one of the plates being folded around the other, of an adjustable hanger seated beneath the folded 125

portion of the plate, and a fastening device connecting the plates and securing the hanger in position, said device being operable for permitting adjustment of the hanger.

5 6. The combination with a screen-frame including a pair of sheet-metal bars each composed of inner and outer plates, a portion of one of the plates of each bar being folded around the other plate of said bar, of adjustable hangers seated beneath the folded portions of the plates, and fastening devices con-

necting the plates and securing the hangers in position, said devices being operable for permitting adjustment of the hangers.

In testimony that I claim the foregoing as 15 my own I have hereunto affixed my signature in the presence of two witnesses.

SIMON WREATON BENSON.
